(57) **CLAIM**

The ornamental design for a kart having a drive unit and a steering unit, as shown and described.

DESCRIPTION

FIG. 1 is a front perspective view showing the new design for a kart having a drive unit and a steering unit;

FIG. 2 is a rear perspective view thereof;

FIG. 3 is a front elevational view thereof;

FIG. 4 is a rear elevational view thereof;

FIG. 5 is a side elevational view thereof;

FIG. 6 is a top plan view thereof;

FIG. 7 is a front elevational view of the drive unit for the kart, the drive unit being shown separately for ease of illustration only;

FIG. 8 is a rear elevational view thereof;

FIG. 9 is a side elevational view thereof;

FIG. 10 is a top plan view thereof;

FIG. 11 is a front elevational view of the steering unit for the kart in a use position, the steering unit being shown separately for ease of illustration only;

FIG. 12 is a rear elevational view thereof;

FIG. 13 is a side elevational view thereof;

FIG. 14 is a top plan view thereof;

FIG. 15 is a side elevational view of the steering unit for the kart in a storage position, the steering unit being shown separately for ease of illustration only; and,

FIG. 16 is a top plan view thereof.

The broken lines shown in the drawings illustrate portions of environmental structure and form no part of the claimed design.
